UNITED STATES PATENT OFFICE.

CHARLES G. LUNDHOLM, OF SAN BERNARDINO, CALIFORNIA, ASSIGNOR TO JOHN J. HANFORD, OF SAN BERNARDINO, CALIFORNIA.

NAIL-PICKING MACHINE FOR BOX-NAILING MACHINERY.

1,108,594.

Specification of Letters Patent. Patented Aug. 25, 1914.

Application filed April 7, 1913. Serial No. 759,288.

To all whom it may concern:

Be it known that I, CHARLES G. LUNDHOLM, a citizen of the United States, and residing in the city of San Bernardino, in the county of San Bernardino and State of California, have invented a new and useful Improvement in Nail-Picking Machines for Box-Nailing Machinery, of which the following is a specification.

10 This invention relates to box nailing machines, and the principal object is to provide a box nailing machine with an efficient nail picker, which automatically picks a nail and pushes the same into a proper chute of a nail 15 chuck.

It is a further object to provide a nail picker with a gravity feed to the picker, and reciprocating means to pick a nail from said gravity means and deliver the same to a nail 20 chuck chute.

In the drawings accompanying this specification Figure 1 is a front elevation of a portion of a box nailing machine showing this invention applied thereto at the upper 25 portion of the machine. Fig. 2 is a side elevation of this invention, a sufficient portion of a box nailing machine being shown to show the operative connection therewith. Fig. 3 is an enlarged detail of one end of the 30 picker mechanism. Fig. 4 is a detail of the same character showing the picker reciprocated, and the pusher about to push the nail into the adjacent chute. Fig. 5 is a transverse section of Fig. 3 on the line 35 5—5 viewed in the direction indicated by the arrows.

This invention is an improvement adapted to be applied to box nailing machines, and particularly to the box nailing machine 40 illustrated and claimed in patent granted to E. E. Northrup, No. 817,509, April 10, 1906.

More specifically in the drawings, 10 and 11 designate the end uprights of the frame of a box nailing machine, as shown in the patent 45 above mentioned, the moving parts mounted thereon being operated from the main shaft 12, driven by any suitable means, one end of the shaft being provided with eccentric 14, on which bears the roller 15 revolvably mounted in the lever 16. This lever is preferably pivoted at the forward portion of the frame and connected by suitable pitman rods to the nail hopper 17 pivotally mounted above the top 18 of the machine. This hopper is pro-

vided in the usual manner with separating 55 partitions 19 and the slots 20 in the floor thereof, the shaking movement imparted to the box by the eccentric 14 throwing the nails with their points down and resting with their heads extending over the sides of 60 the slots.

On the outer face of the eccentric 14 is a crank pin 22 connected by pitman rod 23 to the nailing cross-head 24, which is reciprocatingly mounted adjacent the front of the 65 machine, and preferably inclined slightly to the vertical plane. Also mounted on top of the frame 18 and supported by means of brackets 25, are a plurality of guide-bars 26, a pair of these guide-bars being supported 70 in such position that their upper ends form a continuation of the sides of the slots 20 in the nail hopper, and register therewith at all times. Five pairs of these guide-bars are shown, which are preferably formed of strip 75 metal, having their lower and forwardly extending ends cut away to form the points 28 which just clear the reciprocating picker 29. These bars, as shown, are preferably inclined at an angle of approximately 25° to 80 the horizontal. To the lower portions of these guide-bars are secured the guiding plates 30, so that a narrow channel is formed of approximately the same depth as the length of the nails used, so that the latter 85 are kept in alinement. The guide-way formed by these guide-bars and plates, is of just sufficient width to permit the nail to readily slide there-through. Immediately under the vertical termination of the guide- 90 plates, and provided with a slot to embrace the plates, is the tubular chute 31, the slot being of sufficient depth to permit the nail to pass there-through in suspended position, as clearly shown in Fig. 5, this position being approximately vertical in the vertically 95 disposed chute. As previously stated, the guide-bars terminate immediately adjacent the inner edge of the picker bar 29, which is secured to the bar 32, which is reciprocatingly mounted in slots formed in the blocks 33 and 34, mounted on the top of the table adjacent the front face. The bar 32 is rectangular in cross section in the portion in engagement with the blocks 33 and 34, the 100 end supported in the block 33 being preferably extended as a cylindrical stud outside the frame, provided with an annular ring

35 secured thereto and forming a stop for the coiled spring 36, which normally holds the picker bar in position with the notches 37 on its inner face registering with the guide-way formed by the guide-bars 26. Suitable covering plates hold the bar 32 securely in position in the blocks.

10 Mounted upon the picker bar 29, is a push bar 38, this bar being preferably a flat plate of such width as to clear the fastening bolts of the picker bar 29, and of such length as to closely fit between the inner faces of the blocks 33 and 34. Inclined slots 39 are cut diagonally in this push bar, which are 15 adapted to engage rollers 40, mounted on pins 41 projecting from the upper face of the picker bar. Adjoining these slots 39, are parallel slots 42, which embrace studs 43, which are provided with heads 44 adapted to overlap the sides of the slot and secure the bar in operative relation to its companion bar 29.

20 To reciprocate the bar 29 and its companion pusher bar 38, any suitable means may be used, that shown consisting of a pivoted lever 46 pivoted in bracket 47 secured to the frame 11, the lower end being provided with an inclined cam face 48, which engages with a roller 49, adjustably mounted on the cross-head 24. The upper end of the lever 46 projects into a vertically disposed slot 50 cut in the bar 32, so that the upward movement of the cross-head throws the bar 32, against the tension of the spring 36 with a quick motion, and carries therewith in the notch 37 in the picker bar, a nail from a point opposite the terminal end of the guide-bars and their guideway. As the guide-bar 32 is reciprocated in the direction indicated by the 25 arrow in Fig. 3, the roller 40 takes up against the inclined face of the slot 39 and forces the pusher bar transversely of the picker bar, and at a point where the nail is clear of the adjacent point of a guide-bar, the nail is pushed off of the picker bar, as 30 clearly shown in Fig. 4, and drops into the open mouth of the chute 31, which as shown, is placed slightly eccentric to the median line of the respective guide-ways and the 35 normal position of the notches in the picker bar. The return stroke of the cross-head which quickly carries the roller 49 out of 40 engagement with the lever 46 permits the picker bar and the push bar to regain their 45 normal position under the action of the spring 36, and the next nail of the number 50 normally kept in the guide-ways by the operation of the hopper 17, drops into the adjacent notch 37, and is ready for a repetition

55 of the reciprocation of the picker bar and its companion push bar.

60 It will thus be seen by the use of this invention, a nail is positively delivered to each chute communicating with each nail chuck, at each stroke of the hammer, the tubular chute being of such diameter that the nail 65 is retained in its proper vertical position in its travel to the nail chuck.

65 What I claim is:

70 1. In a box nailing machine, the combination with a slotted nail hopper, of a plurality of bars forming guide-ways extending from said slots in said hopper to a plurality of nail chutes, a reciprocating slotted nail picker arranged to remove nails transversely from said guide-ways, and sliding means to remove the nails from the said picker to deliver the same to the nail chutes.

75 2. In a box nailing machine, the combination with a slotted nail hopper, and a plurality of nail chutes, of a plurality of guide-bars forming a plurality of nail guide-ways registering with the slots in said nail hopper, the lower ends of said bars being cut 80 away and terminating adjacent and vertically disposed over said nail chutes, a reciprocating picker bar mounted transversely and adjacent the terminations of said guide-bars, a push bar arranged to slide across said 85 picker bar, and means to reciprocate said picker bar and slide said push bar co-operatively.

90 3. In a box nailing machine, the combination with a nail hopper, and a plurality of nail chutes leading to nail chucks, the said chutes having slotted upper ends, of a plurality of inclined guide-ways, their upper ends terminating adjacent said hopper and their lower ends provided with guide plates 95 terminating within the slotted upper ends of said chutes, a picker bar provided with notches registering with and adjacent the lower ends of said nail guide-ways, guide pins on said picker bar, a push bar mounted 100 upon said picker bar and having inclined slots to engage said pins, and means to actuate said bars co-operatively, whereby nails are picked from engagement with said 105 guide-ways and deposited in said nail chutes.

110 In witness that I claim the foregoing I have hereunto subscribed my name this 28th day of March, 1913.

CHARLES G. LUNDHOLM.
